US00D404152S

United States Patent [19]**Lynch et al.****Patent Number: Des. 404,152****Date of Patent: **Jan. 12, 1999**[54] **RECHARGEABLE FLASHLIGHT**

[75] Inventors: **Peter F. Lynch**, Skaneateles; **Mark A. Ferguson**, Jamesville; **David A. Furth**, Skaneateles, all of N.Y.

[73] Assignee: **Eveready Battery Company, Inc.**, St. Louis, Mo.

[**] Term: **14 Years**

[21] Appl. No.: **54,932**

[22] Filed: **May 24, 1996**

[51] LOC (6) Cl. **26-02**

[52] U.S. Cl. **D26/37**

[58] Field of Search D26/37-50; 362/157, 362/158, 183-208

[57] **CLAIM**

The ornamental design for a rechargeable flashlight, as shown and described.

DESCRIPTION

FIG. 1 is a perspective view of one embodiment in a rechargeable flashlight in a first configuration;
 FIG. 2 is a front view of a rechargeable flashlight shown in FIG. 1;
 FIG. 3 is a side view of a rechargeable flashlight shown in FIG. 1, the opposite side being a mirror image thereof;
 FIG. 4 is a top view of a rechargeable flashlight;
 FIG. 5 is back view of a rechargeable flashlight opposite that shown in FIG. 2;
 FIG. 6 is a bottom view of a rechargeable flashlight opposite that shown in FIG. 4;
 FIG. 7 is a perspective view of a rechargeable flashlight in a second configuration;
 FIG. 8 is a side view of a rechargeable flashlight shown in FIG. 7;
 FIG. 9 is a top view of a rechargeable flashlight shown in FIG. 7;
 FIG. 10 is a back view of a rechargeable flashlight opposite that shown in FIG. 7; and,
 FIG. 11 is a bottom view of a rechargeable flashlight in the configuration shown in FIG. 7.
